Filed June 18, 1970, Ser. No. 23,554

Term of patent 14 years

Int. Cl. D6—212

U.S. Cl. D6—212

FIG. 1 is a top plan view of a throw rug showing my new design;

FIG. 2 is an edge view thereof taken from the right of FIG. 1;

FIG. 3 is a bottom plan view;

FIG. 4 is a top plan view of a second embodiment of the throw rug design of FIG. 1;

FIG. 5 is an edge view thereof taken from the right of FIG. 4;

FIG. 6 is a bottom plan view;

FIG. 7 is a top plan view of a third embodiment of my design;

FIG. 8 is an edge view thereof;

FIG. 9 is a bottom plan view;

FIG. 10 is a top plan view of a fourth embodiment of my design;

FIG. 11 is an edge view thereof; and

FIG. 12 is a bottom plan view.

The characteristic feature of my invention resides in the grotesque foot-like configuration of the throw rug, which configuration is characterized in having toe-like protuberances extending from one side of the throw rug, and in having a broad base at the other side of the throw rug representing a foreshortened foot without a discernible heel.

I claim:

The ornamental design for throw rug, substantially as shown and described.
